UNITED STATES PATENT OFFICE

157,681

COMBINATION CIGARETTE CONTAINER AND ASH TRAY

Horace S. Hoggatt, Richmond, Ind.

Application May 19, 1949, Serial No. 2,742

Term of patent 3½ years

(Cl. D85—2)

To all whom it may concern:

Be it known that I, Horace S. Hoggatt, a citizen of the United States, residing at Richmond, in the county of Wayne and State of Indiana, have invented a new, original, and ornamental Design for Combination Cigarette Container and Ash Tray, of which the following is a specification, reference being had to the accompanying drawing, forming part thereof.

I claim:

The ornamental design for a combination cigarette container and ash tray, as shown.

HORACE S. HOGGATT.
